Inventor:

I. Bamberger.

UNITED STATES PATENT OFFICE

ISAC BAMBERGER, OF BAD KISSINGEN, GERMANY

FLASH-LIGHT CARTRIDGE

Application filed March 18, 1931, Serial No. 523,421, and in Germany March 14, 1930.

This invention relates to a flash-light cartridge and consists in the provision of a flash-light powder container having an hermetically sealed, conical cover of celluloid or 5 other inflammable material to the apex of which a strip of touch paper or celluloid is connected, said strip projecting into the container as well as in outward direction for the ignition of the powder.

10 Fig. 1 of the accompanying drawings represents a sectional view of the cartridge with detached cover, and

Fig. 2 is a side view of the complete arrangement.

15 The cartridge comprises a container *e* which is charged with flash-light powder *f* and which is formed with a flanged rim *d* to which a conical cover *b* is hermetically sealed. The cover is made of celluloid or other in- 20 flammable material and carries at its apex a strip of touch paper, celluloid or the like. One portion *a* of this strip projects in outward direction, and another portion *a*¹ projects into the container for the ignition of 25 the powder *f*. A highly inflammable tip *c* may be connected to the outer end of the strip for facilitating the firing of the charge.

The cartridge is suspended by means of a bracket *g* on a suitable support. On the 30 strip *a* being ignited, the fire first spreads to and destroys the cover *b* and is then led by the strip portion *a*¹ to the powder for the ignition of the latter.

I claim:

35 1. A flash-light cartridge comprising a flash-light powder container, a conical, inflammable, hermetically sealed cover for said container, and an easily combustible strip connected to the apex of said cover and projecting therefrom into the container as well as in outward direction.

40 2. A flash-light cartridge comprising a flash-light powder container, a conical, hermetically sealed celluloid cover for said container, and a celluloid strip connected to the apex of the cover and projecting therefrom into the container as well as in outward direction.

45 3. A flash-light cartridge comprising a flash-light powder container, a conical, her-

metically sealed celluloid cover for said container, and a touch paper strip connected to the apex of the cover and projecting therefrom into the container as well as in outward direction.

50 4. The device claimed in claim 3 in combination with an inflammable tip on the outer end of the touch paper strip.
